DESIGN FOR A REFRESHMENT BOOTH

Arthur T. Jory, Oakland, Calif.

Application August 2, 1940, Serial No. 94,142

Term of patent 7 years

To all whom it may concern:

Be it known that I, Arthur T. Jory, a citizen of the United States and a resident of Oakland, in the county of Alameda and State of California, have invented a new, original, and ornamental Design for a Refreshment Booth, of which the following is a specification, reference being had to the accompanying drawing, forming part thereof, wherein,

I claim:

The ornamental design for a refreshment booth, substantially as shown.

ARTHUR T. JORY.
